(57) **CLAIM**

The ornamental design for a pallet, as shown and described.

DESCRIPTION

FIG. 1 is a perspective view of a bottom of a first embodiment of a pallet of my new design;

FIG. 2 is a bottom plan view of the embodiment of FIG. 1 thereof;

FIG. 3 is a top plan view of the embodiment of FIG. 1 thereof;

FIG. 4 is a side elevation view of the embodiment of FIG. 1 thereof;

FIG. 5 is an end elevation view of the embodiment of FIG. 1 thereof;

FIG. 6 is a perspective view of the top of the embodiment of FIG. 1 thereof;

FIG. 7 is a perspective view of a bottom of a second embodiment of a pallet of my new design;

FIG. 8 is a bottom plan view of the embodiment of FIG. 7 thereof;

FIG. 9 is a top plan view of the embodiment of FIG. 7 thereof;

FIG. 10 is a side elevation view of the embodiment of FIG. 7 thereof;

FIG. 11 is an end elevation view of the embodiment of FIG. 7 thereof; and,

FIG. 12 is a perspective view of the top of the embodiment of FIG. 7 thereof.
